UNITED STATES PATENT OFFICE.

WILLIAM C. O'BRIEN, OF BALTIMORE, MARYLAND, ASSIGNOR TO MONITOR MANUFACTURING COMPANY, OF BALTIMORE, MARYLAND, A CORPORATION OF MARYLAND.

AUTOMATIC MOTOR-STARTER.

No. 874,531.

Specification of Letters Patent.

Patented Dec. 24, 1907.

Application filed October 23, 1905. Serial No. 284,105.

To all whom it may concern:

Be it known that I, WILLIAM C. O'BRIEN, a citizen of the United States, residing at Baltimore, in the State of Maryland, have 5 invented certain new and useful Improvements in Automatic Motor-Starters, of which the following is a specification.

The purpose of this invention is to provide an automatic starter for electric motors 10 which will operate to cut the starting resistance out of the armature circuit as the motor acquires speed, without the use of dash pots or other mechanical retarding devices.

In the accompanying drawing—Figure 1 15 is a diagrammatic view showing a simple form of starter, having but one resistance section, and having two switches in the circuit which shunts the resistance, the movable parts being shown in their normal positions, and the solenoid being shown in section; Fig. 2 is a similar view showing the positions of the movable parts immediately following the closing of the line switch; Fig. 3 is a similar view showing the positions of the 20 movable parts of the starter while the motor is running under normal conditions; Fig. 4 is a diagrammatic view showing a starter having a series of steps or sections in the starting resistance, and two switches for each shunt 25 circuit, the movable parts being shown in their normal positions in full lines; Fig. 5 is a similar view of the starter shown in Fig. 4, the movable parts being shown in full lines in the positions which they occupy immediately after the closing of the line switch, when the full starting current is flowing 30 through the armature circuit; Figs. 6, 7 and 8 show diagrammatically a starter having a single resistance section with two movable 35 switch members in the circuit which shunts the resistance, both members forming parts of the same switch; Fig. 8^a is a detail showing a modification of the starter illustrated in Figs. 6, 7 and 8, the movable switch members in Fig. 8^a being arranged to engage a 40 fixed member common to both.

The starter illustrated in Figs. 1, 2 and 3, having but a single step in the starting resistance, is especially suited for motors of the 45 smaller sizes, such as those commonly used in shops for operating machine tools, although it may be used for motors of larger sizes which start without load.

Referring to Figs. 1, 2 and 3, L and L' indicate the conductors of a direct current constant potential line circuit, and S indicates

the switch for connecting the line terminals 1 and 2 of the motor starter to the line circuit. The field f of a shunt wound motor M is connected to the line terminals 1 and 2 of the 60 starter by conductors 3 and 4. The circuit of the armature a extends from the conductor 3 through a conductor 5, thence through the coils 6 of a holding magnet H, and thence by a conductor 7 to the coils c of a solenoid C. 65 From the coils of the solenoid the circuit extends through a starting resistance R and thence through a contact block 8. This contact block is connected to one brush of the armature by a conductor 9 and the other 70 brush of the armature, as shown, is connected to the conductor 4. The coils of the solenoid, as well as the starting resistance, are thus connected in series with the armature 75 of the motor.

The solenoid is provided with a core 10 having a contact shoe 11 pivotally connected thereto so that the said shoe may adjust itself to the surface of the contact block 8 and make a good electrical connection therewith 80 when the shoe rests upon the block, as shown in Figs. 1 and 3. The parts 8 and 11 constitute the two members of a normally closed switch S' which is opened by the lifting of the solenoid core when the current at starting exceeds the maximum current which the motor 85 is intended to carry under normal conditions, but remains closed if the current at starting is not in excess of the normal current. The switch member 11 is connected in a circuit, 90 which, when said circuit is closed, forms a shunt around the terminals of the solenoid windings and the resistance R. This shunt circuit, however, is normally open. As shown, the switch member 11 is connected 95 by a flexible conductor 12 and wire 12^a to one member 13 of a normally open switch S^a, the other member 14 being a clip which is connected to the solenoid terminal 7 and arranged adjacent to the magnet H. The 100 switch member 13 normally rests upon a stop z and is located above a rod 15 secured to the solenoid core 10. This rod, as shown, is preferably made of insulating material, although it may be of metal.

When the line switch S is closed to start the motor the magnet H which responds to large or small current strengths will attract its armature and close the switch S^a. If the current flowing in the armature circuit is 110 above normal, the core of the solenoid will rise and open the switch S'. As the magnet

and solenoid are simultaneously energized, the switch S' will be opened before the switch S^2 closes. As long as the armature current remains above a predetermined quantity, the 5 solenoid core will remain in its raised position, as shown in Fig. 2, and the shunt circuit 12, 12^a around the resistance and solenoid coils will remain open. When the current falls to normal, as the motor armature 10 acquires speed, the solenoid core will drop and close the switch S' , while the switch S^2 will remain closed, as shown in Fig. 3. The shunt circuit will then be complete, and the resistance and solenoid coils will be short circuited 15 while the motor is running and until the line switch is again opened. When the line switch is opened to stop the motor, the magnet H becomes deenergized, and the switch-member 13 falls to open position, thus 20 leaving the shunt circuit open, so that when the line switch is again closed the same successive operations will take place.

While the magnet H closes the switch S^2 each time the line switch is closed, whether 25 the current flowing be large or small, the solenoid is arranged to move its core and open the switch S' only in case the armature current, at starting, is above a predetermined quantity,—usually but not necessarily the 30 maximum current which the motor is designed to continuously carry. This predetermined quantity is herein referred to for convenience as the normal armature current. If, therefore, the current does not exceed this 35 predetermined quantity when the line switch is closed to start the motor, the switch S^2 will close and the switch S' will not open, and the resistance and solenoid will be immediately cut out, the current flowing directly to the 40 motor through the shunt circuit as soon as the switch S^2 closes.

Ordinarily, the current at starting is sufficient to lift the solenoid core, and, where the motor always starts with a current above the 45 current required to move the solenoid core, the core may be used to operate both switches, by arranging the switch member 13 above the rod 15, as shown, so that the rod will move said member upward into position 50 where it will be acted upon and held by the magnet. In any case, where the current is above the predetermined quantity, the switch S' will open before the switch S^2 closes, so that the resistance cannot become short-circuited until the current falls to normal. 55

In Figs. 4 and 5 I have shown a starter having a resistance arranged in sections or steps with a series of electro-magnetically operated devices for short circuiting these sections successively, the principle of operation 60 being the same as in the previously described figures. In these views C' , C^2 , C^3 and C^4 , indicate solenoids having cores arranged to respond to successively greater excess currents 65 in the armature circuit and H' indicates a so-

lenoid having a core which responds to currents of any strength. The solenoids C' to C^4 inclusive are substantially the same as the solenoid C in Figs. 1, 2 and 3, and the solenoid H' corresponds in function to the magnet 70 H of said figures. As shown in Fig. 4, the coils of the various solenoids are connected in series with one another and with the resistance sections R' to R^4 inclusive, and the motor armature a . Thus the line terminal 75 1 is connected to one terminal of the coils of the solenoid H' by a conductor 25 and the other terminal of said coils is connected by a conductor 16 to the coils of the adjacent solenoid C^4 . From these coils the armature 80 circuit extends by conductor 17 through one section R^4 of the resistance and thence to the contact block or switch member 8 of a normally closed switch S^6 . From said contact block the armature circuit extends through a 85 conductor 16^a to the coils of the next solenoid C^3 in the series and thence by conductor 17^a to the next section R^3 of the resistance and thence to the contact member 8 of a normally closed switch S^5 . In the same manner 90 the circuit extends through successive solenoid coils C^2 and C' , resistance sections R^2 and R' and members 8 of switches S^4 and S^3 , through the conductors 16^b, 17^b and 16^c, 17^c. The member 8 of the normally closed switch 95 S^3 is connected by the conductor 18 to one brush of the armature a and the opposite brush is connected by the conductor 4 to the line terminal 2. The field f of the motor is connected to the line terminal 1 by a conductor 3. The normally closed switches S^3 to S^6 inclusive are the same as the normally closed switch S' in Figs. 1, 2 and 3, and the switch members 11 of these switches are connected respectively by separate conductors 100 12^b to 12^d, inclusive, to separate members 14^a to 14^d, inclusive, which form parts of normally open switches S^7 . The core 13^b of the solenoid H' carries at its upper end a contact plate or switch member 13^e, adapted, 110 when the core is moved upward, as shown in Fig. 5, to connect each of the low resistance circuits 12^b to 12^e inclusive, with the line terminal 1 through a flexible conductor 19 which is attached to the member 13^e and connected to the conductor 25. The solenoid 115 H' is made so that its core will move upward when either a small or a large quantity of current is flowing through its coils, and in order to make this solenoid sensitive to small 120 currents the weight of the core 13^b may be partly counterbalanced by springs 20. While the solenoid H' will respond to current of any volume which may flow in the armature circuit, and thus cause the switch member 13^e 125 to close the normally open switches in the shunt circuits 12^b—12^e, the solenoids C' to C^4 , inclusive, respond only to currents which are in excess of the normal current which it is intended that the motor shall carry, and these 130

solenoids, in succession, respond to successively greater current strengths. These solenoids may be constructed to act under various current strengths in any well-known way. For convenience of illustration I have shown the solenoids of uniform size, but with successively larger weights w upon rods 15^a which are attached to cores 10, so that the solenoids will operate with successively 10 greater current strengths.

In Fig. 5 the circuits are the same as in Fig. 4, except that instead of connecting the coils of the solenoid H' in series with the solenoids C' to C⁴ inclusive, I have shown, as a 15 modification, the coils of the solenoid H' connected directly to the wires 3 and 4 by conductors 21 and 22, and the wire 16, connected to the coil C⁴, is also connected to the conductor 3. It is immaterial whether the coils 20 of the solenoid H' are connected across the line, as shown, or in series with the other solenoids so long as current is admitted to all of the solenoids at the same time.

In operation when the line switch S is 25 closed, the current flows through the coils of all of the solenoids and through the starting resistance to the armature. Whether the current immediately following the closure of the line switch, is large or small, the solenoid 30 core 13^b moves upward and the switch member 13^c, actuated thereby, engages the switch members 14^a to 14^d inclusive, and connects the shunt circuits 12^b–12^c to the line terminal 1. If the current flowing in the armature 35 circuit is not in excess of the normal, no one of the solenoids C' to C⁴ inclusive will move its core, and, therefore, the current will flow directly to the armature from the switch contact 14^a through the shunt circuit 12^b and 40 switch S³. The core 13^b will remain in its raised position as long as the line switch is closed, and it will be seen that all of the resistance, as well as the coils of the solenoids C' to C⁴ inclusive, will be short circuited through 45 the conductor 12^b. If, however, the starting current should be only slightly in excess of the normal, at the time the line switch is closed, the core of the solenoid C' will lift simultaneously with the upward movement 50 of the core of the magnet H' and the normally closed switch S³ will be opened before the switch member 13^c closes the circuit through the conductor 12^b. The current, therefore, instead of flowing through the 55 shunt circuit 12^b to the armature will then flow from the contact 14^b through shunt circuit 12^c, switch S⁴, conductor 16^c, coils of solenoid C', conductor 17^c, resistance section R' and conductor 18 to the armature. The 60 resistance section R' will, therefore, be inserted in series with the motor armature, and as soon as the current falls to the normal the core of the solenoid C' will drop and close the switch S³, thus cutting out said section of the 65 resistance. In a similar manner if the cur-

rent is great enough to actuate the solenoid C², it will also actuate the solenoid C' and the armature current will then flow through shunt circuit 12^d, solenoids C² and C' and resistance sections R² and R' and the two sections R' 70 and R² of the resistance will be maintained in series with the armature until, as the current falls, the core of the magnet C² will first drop, thus closing the shunt circuit 12^e and cutting out the resistance section R² and 75 then, with a further fall in current, the core of the solenoid C' will drop, cutting out the resistance section R'.

If the current at starting is great enough to actuate all of the solenoids C' to C⁴ inclusive, these will open the switches S³ to S⁶ inclusive, before the shunt circuits 12^b to 12^e inclusive are completed at the switches 14^a to 14^d inclusive, and all of the resistance sections R' to R⁴ inclusive, will thus be in series 85 with the motor as shown in Fig. 5. As the current falls to normal, it will be obvious that the solenoid cores which operate the normally closed switches will drop in succession, from left to right in the drawing, thus cutting 90 out the resistance sections gradually and successively according to the rate at which the current in the armature circuit diminishes.

The electro-magnetic device H' for closing the normally open switches in the shunt circuits may be used in connection with as many of the devices for operating the normally closed switches as may be desired. It will be noted that the starter requires no mechanical retarding devices and that it affords positive protection to the motor from excessive currents in starting, since the solenoids prevent short circuiting of the resistance as long as the starting current is above the normal.

In Figs. 6 to 8 inclusive, I have illustrated starters operating upon the same principle as the previously described figures, but in Figs. 6 to 8 inclusive, there is only one switch in each shunt circuit, this switch being normally open. This switch, however, has two movable switch-members, one normally in position to be engaged by the other to close the low resistance shunt circuit, and movable from said position, which may be called its closed position, only when 105 the starting current in the armature is above a predetermined quantity, and the other member being normally in position to maintain the shunt circuit open and movable from said position, which may be called its open position, into position to engage, or to be engaged by, the first mentioned member each time the line switch is closed.

Referring to Figs. 6, 7 and 8, which represent a starter, suitable for the small sizes of 125 motors in which the resistance is cut out at a single step, C indicates an ordinary solenoid arranged in the armature circuit of the motor M and adapted to move its core 10 upward only when the current at starting is in 130

excess of the normal current which the motor is designed to carry, and H' indicates a solenoid sensitive to large or small currents and adapted to move its core 13^b upward each time the line switch is closed and to hold said core in its upper position as long as current is passing through the motor. As shown one terminal 25 of the solenoid C is connected to the line terminal 1 and the other terminal 27 is connected to one terminal of the resistance R. From the resistance R the armature circuit extends through conductor 28 to the coils h of the sensitive solenoid and thence by conductor 29 to the armature a of the motor. The conductors 3 and 4 are connected to the motor in the same manner as in the previously described figures. In these figures the core 10 of the solenoid C, which is arranged directly above the core of the solenoid H' , forms part of the shunt circuit which, when the motor is in operation, is completed around the coils of the solenoid C and the starting resistance R. As shown a rod 15^b of non-magnetic metal is attached to the core 10 and carries a stop 30 which limits the downward movement of the core. The core is electrically connected to the terminal 26 by a flexible conductor 31 which, as shown, is attached to the stop 30. The core 13^b of the magnet H' also has connected to it an upwardly extending rod 13^c , of non-magnetic material which may be either metal or a non-conductor, and this upward extension carries a block 8^a of conducting material which is electrically connected to the conductor 28 by a flexible conductor 32. The block 8^a forms one member of a normally open switch S^7 and also serves as a stop to limit the downward movement of the core 13^b . The part 11^a connected to the core 10 forms the other member of said normally open switch.

Fig. 6 represents the normal positions of the parts, when the line switch S is open and the motor is stopped. In this position it will be noted that the switch S^7 is open. When the line switch S is closed to start the motor, if the current in the armature circuit at the moment when said switch is closed is in excess of the normal armature current, the cores of both solenoids will be drawn up simultaneously, as shown in Fig. 7, and the switch S^7 will, therefore, remain open until the current in the armature current falls to normal, as the motor acquires speed, when the core of the solenoid C will fall and the switch member 11^a will engage the switch member 8^a , as shown in Fig. 8. As soon as the switch S^7 is thus closed current will flow through the conductor 31, rod 15^b , core 10, switch S^7 and conductor 32, thus short circuiting the coils of the solenoid C and the resistance R. As the solenoid H' responds to either large or small currents its core will be held in its upper position as long as the line switch is closed and current is flowing

through the motor. It will, therefore, support the core 10, as shown in Fig. 8, after the coils of the solenoid C have been short circuited and the current will continue to flow through the low resistance shunt circuit until the line switch S is opened and the sensitive solenoid H' thereby deenergized, when the core of said latter solenoid will drop into the position shown in Fig. 6, thus leaving the shunt circuit open. 75

If the current in the armature circuit at the same time when the line switch is closed should not exceed the normal armature current, the core of the solenoid C will not be lifted but the core of the solenoid H' will move upward carrying the switch member 8^a into engagement with the switch member 11^a, as shown in Fig. 8, thus closing the shunt circuit and short circuiting the coils of the solenoid C and the starting resistance R. 80 The starting resistance will, therefore, be cut immediately out of the circuit by the device described if the motor takes normal current, or less, at starting; but if the current is in excess of the normal the starting resistance 85 will not be cut out until the armature current falls to normal. It is immaterial whether the sensitive solenoid H' be connected in series, as shown, or across the line so long as the two solenoids are simultaneously energized when the line switch is closed. 90

In Fig. 8^a I have shown a fixed stop x of conducting material which is interposed between the two movable switch members 8^a and 11^a. This stop connects the two movable switch members electrically when the motor is in operation, and it prevents the lower member 8^a from striking the upper member and causing the upper member to be thrown upward when the starting current is 100 insufficient to cause the upper solenoid to lift its core. Under these conditions the lower movable member moves up, as indicated in dotted lines, into engagement with the stop or stationary switch member, on which the 105 upper movable member rests. This stop is desirable for these conditions of small starting current, but, where the current is always sufficient to lift both movable switch members, the lower one comes to its upper position and is strongly held there, as shown in Fig. 7, forming a firm support which is not affected by the falling of the upper member upon it, and with the larger current the stationary stop or switch member is not essential. 115

In the various forms of my invention shown the starting resistance is normally arranged in series with the armature so that the armature is protected by the resistance 125 and the full starting current can flow through the armature as soon as the line switch is closed to complete the motor circuits. Whether the normally closed switch member in a shunt circuit moves to open position or 130

remains in closed position depends upon the quantity of starting current flowing through the armature circuit in the interval between the closing of the line switch and the closing 5 of the normally open switch in said shunt circuit. If this quantity is above a predetermined value during said interval, the solenoid controlling the normally closed switch member moves said member to open position 10 before the normally open member reaches the closed position, and if below said value the normally closed member remains stationary and the resistance section and solenoid coils are at once short circuited by the 15 completion of the shunt circuit through the normally open member, which is moved to closed position each time the line switch is closed. Where the starting current,—that is, the current which flows through the resistance to the armature to start the motor,—is not in excess of the predetermined 20 safe quantity, no time element enters into the operation of short-circuiting the resistance other than the brief interval required 25 for the normally open switch to be moved into closed position by its magnet.

Having thus described my invention what I claim and desire to secure by Letters Patent of the United States is—

30 1. In an automatic starter for electric motors, a starting resistance in the armature circuit, a normally open low-resistance circuit in shunt to said starting resistance, two movable switch members in said shunt circuit, an electro-magnetic device adapted to move one of said members to closed position each time the line switch is closed, and an electro-magnetic device adapted to move the other member to open position only when 40 the armature current at starting is above a predetermined quantity.

2. In an automatic starter for electric motors, a starting resistance in the armature circuit, a normally open low-resistance circuit in shunt to said starting resistance, two movable switch members in said shunt circuit, an electro-magnetic device adapted to move one of said members to closed position each time the line switch is closed, and an 45 electro-magnetic device adapted to move the other member to open position only when the armature current at starting is above a predetermined quantity, said electro-magnetic devices being connected so as to be simultaneously energized when the line switch is closed.

3. In an automatic starter for electric motors, a starting resistance in the armature circuit, an electro-magnetic device having 60 coils in said circuit, a normally open low-resistance circuit in shunt to said coils and resistance, two movable switch members in said shunt circuit, one adapted to be opened by said device when the armature current at

starting exceeds a predetermined quantity, 65 and an electro-magnetic device arranged to move the other member to closed position each time the line switch is closed.

4. In an automatic starter for electric motors, a starting resistance in the armature circuit, an electro-magnetic device having coils in said circuit, a normally open low-resistance circuit in shunt to said coils and resistance, two movable switch members in said shunt circuit, one adapted to be moved 70 to open position by said device when the armature current at starting exceeds a predetermined quantity, and an electro-magnetic device arranged to move the other member to closed position each time the line 75 switch is closed.

5. In an automatic starter for electric motors, a starting resistance in the armature circuit, an electro-magnetic device having coils in said circuit, a normally open low-resistance circuit in shunt to said coils and resistance, two movable switch members in said shunt circuit, one adapted to be moved 80 to open position by said device when the armature current at starting exceeds a predetermined quantity, and an electro-magnetic device responsive to currents of less strength than said predetermined quantity adapted 85 to move the other switch member to closed position.

6. In an automatic starter for electric motors, a starting resistance for the armature circuit, an electro-magnetic device having windings in said circuit, a normally closed switch and a normally open switch arranged 100 in a low-resistance circuit adapted to shunt said resistance and windings, said device being arranged to open said normally closed switch only when the armature current at starting is above a predetermined quantity, 105 and electro-magnetically operated means adapted to close said normally open switch after current has been admitted to said windings.

7. In an automatic starter for electric motors, a starting resistance for the armature circuit, an electro-magnetic device having windings in said circuit, a normally closed switch and a normally open switch arranged 110 in a low-resistance circuit adapted to shunt said resistance and windings, said device being arranged to open said normally closed switch only when the armature current at starting is above a predetermined quantity, 115 and an electro-magnetic device, responding to small current strengths arranged to close said normally open switch after current has been admitted to said windings.

8. In an automatic starter for electric motors, a resistance arranged in the armature circuit, a low resistance circuit in shunt to said starting resistance, a normally closed switch and a normally open switch in said

- shunt circuit, and electromagnetic means for first opening said normally closed switch and then closing said normally open switch when the current is turned on.
5. 9. In an automatic starter for electric motors, a starting resistance in the armature circuit, an electro-magnetic device having coils in said circuit, a low resistance circuit in shunt to said starting resistance and coils, a 10 normally closed switch in said shunt circuit adapted to be opened by said electromagnetic device when the starting current in the armature circuit exceeds a predetermined quantity, a normally open switch in said 15 shunt circuit and means for closing said latter switch after the normally closed switch has opened.
10. In an automatic starter for electric motors, a starting resistance in the armature 20 circuit, an electro-magnetic device having coils in said circuit, a low resistance circuit in shunt to said coils and said starting resistance, a normally closed switch in said shunt circuit adapted to be opened by said device 25 when the armature current at starting is in excess of a predetermined quantity, and a normally open electro-magnetically controlled switch in said shunt circuit adapted to close after the normally closed switch has 30 opened and to remain closed while the motor is in operation.
11. In an automatic starter for electric motors, a starting resistance in the armature circuit and an electro-magnetic device having 35 coils in said circuit, a low resistance circuit in shunt to said starting resistance and coils, a normally closed switch in said shunt circuit adapted to be opened by said device when the starting current in the armature 40 circuit exceeds a predetermined quantity, and an electro-magnetically controlled normally open switch in said shunt circuit arranged to close when current is admitted to the armature.
45. 12. In an automatic starter for electric motors, a starting resistance in the armature circuit, a solenoid having windings in said circuit, a low resistance circuit in shunt to said windings and starting resistance, a core 50 adapted to be lifted by said solenoid when the starting current in the armature circuit exceeds a predetermined quantity, and to fall by gravity when the current falls to normal, a normally closed switch in said shunt 55 circuit adapted to be opened by the upward movement of said core, and a normally open switch in said shunt circuit arranged to close after said core has moved upwardly, and means for holding said normally open switch 60 in closed position while the motor is running.
13. In an automatic starter for electric motors, a series of resistance sections in the armature circuit, a plurality of electro-magnetic devices each having windings in said 65 circuit, low-resistance circuits arranged to shunt said resistance sections and windings, a normally open switch and a normally closed switch in each shunt circuit, each of said devices being adapted to open one of said normally closed switches, and said devices being 70 arranged to respond in succession to successively greater quantities of starting current, and electro-magnetically operated means adapted to close said normally open switches after current has been admitted to said 75 windings.
14. In an automatic starter for electric motors, a series of resistance sections in the armature circuit, a plurality of electro-magnetic devices each having windings in said 80 circuit, low-resistance circuits arranged to shunt said resistance sections and windings, a normally open switch and a normally closed switch in each shunt circuit, each of said devices being adapted to open one of said 85 normally closed switches and said devices being arranged to respond in succession to successively greater quantities of starting current, and an electro-magnetic device responding to small current strengths, arranged to close said normally open switches after current has been admitted to said windings.
15. In an automatic starter for electric motors, a starting resistance normally arranged in the armature circuit, an electro-magnetic device having its windings in said circuit, a normally open low resistance circuit in shunt to said resistance and windings, two independently movable switch members 100 in said shunt circuit, one of said members being normally in closed position and movable by said device to open position only when the starting current is above a predetermined quantity, the other of said members being 105 normally in open position, and an electro-magnetic device for moving said latter member to closed position each time current is admitted to the armature.
16. In an automatic starter for electric 110 motors, a starting resistance arranged in series with the armature, an electromagnetic device having its windings in series with said resistance and armature, a normally open low resistance circuit in shunt to said resistance and windings, a switch member in said shunt circuit normally in closed position and movable by said device to open position only when the starting current exceeds a predetermined quantity, a switch member in said 115 shunt circuit normally in open position, and means for moving said latter member to closed position each time current is admitted 120 to the armature.
17. In an automatic starter for electric 125 motors, a starting resistance and a solenoid arranged in series with the armature, a normally open low resistance circuit in shunt

to said starting resistance and solenoid, a switch member in said shunt circuit, normally in closed position, and adapted to be moved to open position by said solenoid only 5 when the starting current is above a predetermined quantity, a switch member in said shunt circuit normally in open position, and means for moving said latter member into

closed position each time current is admitted to the armature.

In testimony whereof I affix my signature, 10 in presence of two witnesses.

WILLIAM C. O'BRIEN.
